FIG. 1

INVENTOR,
ALLAN ANTHONY

BY Donald E. Mochling

ATTORNEY

UNITED STATES PATENT OFFICE

169,798

LAMP FIXTURE

Allan Anthony, Maywood, Ill.

Application June 17, 1952, Serial No. 20,238

Term of patent 14 years

(Cl. D48—31)

To all whom it may concern:

Be it known that I, Allan Anthony, citizen of the United States, residing at Maywood, State of Illinois, have invented a new, original, and ornamental Design for a Lamp Fixture, of which the following is a specification, reference being had to the accompanying drawing, forming a part thereof.

Fig. 1 is a side elevational view of a lamp fixture showing my new design; and

Fig. 2 is a top plan view thereof.

I claim:

The ornamental design for a lamp fixture, substantially as shown.

ALLAN ANTHONY.
